UNITED STATES PATENT OFFICE.

CHARLES E. DATH, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed June 27, 1924. Serial No. 722,756.

To all whom it may concern:

Be it known that I, CHARLES E. DATH, a citizen of the United States, residing at Chicago, in the county of Cook and State of Illinois, have invented a certain new and useful Improvement in Hand Brakes for Railway Cars, of which the following is a full, clear, concise, and exact description, reference being had to the accompanying drawings, forming a part of this specification.

This invention relates to improvements in hand brakes for railway cars.

Such invention is broadly directed to improvements in hand brakes for railway cars of the mail and baggage type, in which the brakes are usually located on the end walls of the car, and arranged so that they may be operated either from the interior or the exterior of said car, such operating means usually including a depending lever in the interior of the car, and a similar lever on the outside of said car. In railway cars of this description, the space available for the operation of the brake lever in the interior of the car is very limited, especially because of the disposition of heating coils and other fixtures adjacent the lever, so that efficient operation thereof is rendered very difficult and even dangerous, the operative stroke of the lever being toward the side wall of the car, and the hands of the operator very frequently are brought into contact with the heating coils, or strike against adjacent portions of the car.

The principal object of this invention is to provide operating means for the brake, which entirely eliminate the disadvantages incident to the constructions heretofore used, and more specifically, provide means, including a particular type of lever, disposed in a manner freely accessible to the operator without awkwardness, or incurring the danger of striking his hands against the heating pipes, or parts of the car, the lever being disposed at a point removed from the heating coils and being movable on its operative stroke away from the side wall of the car toward the unobstructed center portion of the car.

Another object of the invention is to provide a brake device of this character with a depending lever on the outside of the car for operating the brake, and an upstanding

lever on the inside of the car for this purpose, this construction having the advantage that it affords the most efficient disposition of the levers for operation, both inside and outside of the car.

Other objects and advantages of the invention will more clearly appear from the description and claims hereinafter following.

In the drawings forming a part of this specification, Figure 1 is an elevational view of the outer end of a brake mechanism adapted to be operated either from the outside or inside of the car, illustrating a particular type of operating lever associated therewith. Figure 2 is a side elevational view of the structure shown in Figure 1, illustrating the brake applied to the end wall of a car, the end wall being shown partly broken away and in vertical section, and the location of the usual steam heating coils being shown in dotted lines. Figure 3 is an elevational view of the inner end of the brake mechanism illustrated in Figure 2, showing my improved type of lever in operative position in full lines, and at the limit of its operative movement in dotted lines, the side wall of the car being indicated diagrammatically. Figure 4 is a horizontal, sectional view, on a reduced scale, of a portion of the end of a car, illustrating the relative location of the brake mechanism, and the usual steam coils.

In the drawings, the end wall of the mail or baggage car is indicated by 10, and one of the side walls of the car by 11. The end wall 10 is shown as provided with a door opening 12, and mounted at the corner of the car, adjacent the end and side walls thereof, are the usual steam coils 13-13. A hand brake mechanism A, of well known construction, is mounted on the end wall 10 of the car, the same being of that type which is adapted for operation from either the inside or the outside of the car.

The brake mechanism A includes an outer housing 14, and an inner housing 15. The outer housing is provided with the usual winding drum 16, having mounted thereon a ratchet wheel 17, co-operating with a spring pressed pawl 18, which is adapted to be actuated by means of the releasing lever 19. An operating lever 20 is provided which is pivotally secured as at 21 to the link 22, which is arranged to swing about

the axis of the ratchet wheel 17, a slot 23 being provided in the edge of the housing 14 as shown in Fig. 1, to permit the swinging action of the lever 20. The lever 20 has a portion 24 on its inner end, provided with a tooth 25 for engagement with the ratchet wheel 17, and the portion 24 has an extension 26 which reaches beyond the upper end of the slot 23, such extension serving as a stop to limit the downward swinging of the lever to a position where the tooth 25 is held out of engagement with the ratchet wheel 17 by the weight of the lever, and it is here pointed out that the slot 23 also serves to limit the upward movement of the lever 20, so that the same will always return to its normally depending position by gravity.

The housing 15 is also provided with a ratchet wheel 27, connected with the drum 16 through the medium of the shaft 28, which extends through the wall 10 and the housing 15 as shown. A lever 29 is mounted in the housing upon the shaft 29', which extends through the wall 10 into the housing 14, this being the shaft which carries the pawl 18, so that a movement of the lever 29 will operate such pawl in the same manner as movement of the lever 19. In connection with the foregoing description, reference may be had to Patent No. 1,240,324 granted to William Dwyer, September 18, 1917, as this invention contemplates an improved type of construction shown in this patent, utilizing the mechanism above described in combination with novel means for overcoming defects incident to the type of brake shown in such patent.

It will be observed that the lever 29 is oppositely disposed with respect to the lever 19, this being for the purpose of affording a more convenient means for releasing the pawl 18, and to mount the lever out of the way of operating mechanism hereafter described.

A link 30 is mounted in the housing 15 in position to swing about the axis of the ratchet wheel 27 in the same manner as the link 22, and pivotally connected to the link 30 as at 31, is a lever 32, adapted to swing with the link 30, there being a slot 33 in the housing 15 to permit this swinging movement. The lever 32 is provided at its inner end with a ratchet operating portion or arm 34, having a tooth 35 for engagement with the ratchet wheel 27, and an extension 36 projecting beyond the upper end of the slot 33, to provide a stop to limit the downward movement of the lever. The lever 32 has a portion 37 extending at an angle thereto as shown, and then having an inclined portion 38 extending substantially in the direction of the ratchet operating portion 34, and having a handle portion 39 turned inwardly toward the ratchet portion 34. The

angular portion 37 of the lever is long enough to reach the upper end of the slot 33, as shown in the drawing in dotted lines, thus affording clearance for the inclined portion 38. The path of the lever 32 is indicated in dotted lines in Fig. 3 and it will be noted that the upper end of the slot 33 limits the movement so that the lever when at the limit of its operative stroke is in an overbalanced position and will return by gravity to its normally inoperative position as shown in full lines in Fig. 3, when released.

To operate the brakes from the outside of the car the hand grip at the free end of the lever 20 is grasped, and the same oscillated, thereby swinging the lever 20 and the link 22, thus bringing the tooth 25 into engagement with the ratchet wheel 17 and rotating the drum 16 to tighten the brakes. Upon release of such lever it will return to inoperative position by its own weight, releasing the tooth 25 from engagement with the ratchet. The lever 20 is thus normally in a depending position so that the same is in the most advantageous position for operation from the outside of the car. It will be observed that the movement of the lever 20 on its operative stroke is toward the side wall 11 of the car, attention being called to this fact when considering the movement of the lever 32. This lever upon the inside of the car is held in a normally upstanding position, and its operative stroke is away from the side wall of the car toward the center thereof, such stroke of the lever serving to engage the tooth 35 with the ratchet wheel to rotate the drum 16 and tighten the brakes, the movement of such lever being limited by the upper end of the slot 33, so that when the lever is released, it will fall to inoperative position by gravity, thereby disengaging the tooth 35 from the ratchet.

By the above described arrangement it will be understood that the operating lever 20 on the outside of the car is normally in a depending position, and its operative stroke is toward the side wall of the car, which is the most efficient stroke when the brake is operated from outside of the car. While the lever 32 on the inside of the car is normally in upstanding position and removed from the heating pipes, and its operative stroke is away from the wall of the car toward the center thereof, so that the path of movement of the lever is entirely unobstructed and a maximum amount of force can be applied thereto without assuming an awkward position; and finally both levers return to normally inoperative position through gravity.

While I have herein shown and described what I now consider the preferred manner of carrying out the invention, the same is

merely illustrative and I contemplate all changes and modifications that come within the scope of the claims appended hereto.

I claim:

5. 1. In a construction of the character described, the combination with a railway car having side and end walls, there being obstructions along said side wall such as steam pipes, said end wall being equipped with a hand brake of the inside and outside type and comprising a rotatable shaft extending through said wall and being provided with a winding drum, and ratchet wheels adjacent the inner and outer ends of said rotatable member; said ratchet wheels being movable in a clockwise direction with reference to said side wall to wind the brake chain on said drum, said brake being provided with inner and outer housings having openings 20 on their under sides to permit access to said ratchet wheels; of a depending lever arranged at the outer side of said end wall and having pawl means adapted to rotate said ratchet wheel to wind said brake chain when moved in a direction toward the plane of said side wall; and a continuous lever on the inside of said car, extending through the opening at the bottom of the inside housing, said lever being inclined upwardly between the side wall and adjacent housing to clear the obstructions on the side wall, said lever being accessible above said housing and having pawl means associated therewith adapted to rotate the inside ratchet wheel to wind 35 the chain when the lever is moved in a direction away from the plane of said side wall.
2. In a hand brake mechanism of the inside and outside type, comprising inner and outer housings, and a rotatable member extending into said housings and having similarly disposed ratchet wheels thereon adjacent its opposite ends, said rotatable member having means providing a winding drum, and said inner and outer housings having openings at the under sides thereof permitting access to the ratchet wheels; of a lever

extending into the opening in the under side of one of said housings and having pawl means adapted to rotate the related ratchet 50 wheel to wind the chain when moved in a direction away from a vertical plane extending through and coincident with said rotatable member; and a curved lever extending into the opening on the under side of the 55 other of said housings, said lever having pawl means adapted to rotate the related ratchet to wind the chain when said latter lever is moved in a direction toward said vertical plane. 60

3. In a hand brake mechanism, the combination with a winding drum; of means for rotating said drum to effect application of the brakes, said means including a ratchet member rotatable about a horizontal axis; 65 and a pivoted, toothed operating member for said ratchet member, said operating member being swingable about said horizontal axis, the toothed portion of said operating member being disposed below said axis and engageable with the under side of said ratchet member, said operating member including a laterally extending lever arm rigid therewith, said lever arm having an angularly disposed section providing a 70 hand grip portion, said operating member being movable in one direction to engage the toothed portion with the ratchet member and effect winding of the drum and movable in a reverse direction to disengage the 75 toothed portion from said ratchet member; and stop means for limiting the range of movement of said lever in both directions, and serving to dispose the major portion of said lever above the pivotal axis thereof 80 during said entire range of movement, whereby the weight of said lever when released effects disengagement of said toothed portion from said ratchet member. 85

In witness that I claim the foregoing I have hereunto subscribed my name this 20th day of June 1924.

CHARLES E. DATH.
